HEAD BRACKET

Charles C. Gill, Verne L. Julian, John W. McIlwraith, and Charles F. Rutledge, Elwood, Ind., assignors of one-half to John W. McIlwraith and one-half to Charles F. Rutledge, both of Elwood, Ind.

Application July 29, 1932. Serial No. 625,792

9 Claims. (Cl. 20—20)

This invention relates to a head structure for an overhead door and of the general character illustrated in the co-pending applications, Serial No. 498,698, filed Nov. 28, 1930, entitled, Flexible doors, and Serial No. 614,894, filed June 2, 1932, entitled Folding sectional door.

The chief object of this invention is to provide a head structure that may be economically and cheaply manufactured and so arranged that it 10 may be readily adapted to different sized doors with but a minimum duplication of slightly dissimilar parts and whereby the maximum number of parts is capable of utilization with different sized doors.

15 Another object of the invention is to incorporate in the head structure an integral mounting for a pulley, the same being associated with a cable, in turn connected to the door and counterbalancing associated therewith.

20 The chief feature of the invention, in addition to the accomplishment of the foregoing objects, consists in the detailed construction of the head structure and included parts.

The full nature of the invention will be understood from the accompanying drawing and the following description and claims:—

In the drawing, Fig. 1 is a side elevation of one 25 of the head structure embodying the invention, the full lines indicating parts arranged for one size of door and the dotted lines indicating similar parts arranged for a second size door.

Fig. 2 is an enlarged sectional view taken on line 2—2 of Fig. 1 and in the direction of the arrows and showing the track.

30 Figs. 3 and 4 are elevational views taken at right angles of a part that may be associated with the portion of the head structure for adapting said head structure to another size of door from a predetermined size of door.

40 In Figs. 1 and 2 of the drawing, 10 indicates a plate which is approximately of triangular shape, the hypotenuse of which consists of two curves that merge with each other, the upper curve being generally indicated by the numeral 11, 45 while the lower is indicated by the numeral 12, the former being inwardly directed and the latter being outwardly directed. The lower end of the plate 10 terminates in a portion 13 adapted to register with a vertical track, the cross section of which is the same as that shown in Fig. 2 for the lower portion of said head structure.

As indicated in Fig. 2, a perpendicular flange 14 extends from the side 15 at one end thereof, the side 15 being inclined or offset at 16 and terminating in a track portion 17 and a retaining

wall portion 18. The purpose of the inclination is to space the track portion from the back or side portion 15 so that the retainers for the guide shoes or wheels that engage the track portions 14 and 17, or both, will be spaced from the side wall so that the supports for the guides can project beyond the rollers, shoes or guides for anchorage or retention of the same thereon without the supports and the anchorage engaging the track side or back 15.

As shown in the last two before mentioned applications the head structure includes a front vertical wall 14 which is interrupted intermediate its ends and terminates in a forwardly and upwardly curved socket forming portion 19. The top 20 of the socket is directed inwardly and downwardly and is formed by a separate strap that includes a curved portion 21 and a straight portion 22, the same lying parallel to the portion 14 and terminating as at 23 short of engagement with the upwardly and rearwardly directed grooved portion of the head structure forming an opening therebetween for the passage of certain of the guide members which, as before stated, may be in the form of shoes, rollers or slides. The body portion 10 of the head structure includes transverse portions 24 that are rigid with the head structure and are struck therefrom as at 25 and the same are spot-welded or otherwise secured to the vertical strap 22. 55 The grooved portion of the trackway, shown in Fig. 2, is continued throughout the length of the curves 11 and 12 and the curve 11 terminates in an inwardly directed portion 26 that serves as a stop preventing the folded doors from moving upwardly an excessive amount above the horizontal, a certain amount of said movement, however, being necessary in order to insure forward seating of one of the guide members in the socket indicated by the numerals 20 and 19.

Plate 10 is apertured as at 27 and supports a pivot 28 which supports an arm 29 that is rigid with a combination track and switch having the depending portion 30 and the upper portion 31. Normally this member is positioned so that the guide member bearing upon portion 12 will pass beneath the lower end of the member 30 and travel along the portion 11 and will then engage the portion 31 to tilt the switch track into the full line position shown so that the second guide member passing along section 12 will engage the end of the member 30 and ride upon the inside of the member 30 in the continued upward movement of the second guide member.

As shown in Fig. 1, the back portion of the

vertical portion of the track is relieved and there is suitably secured thereto, as at 32, the member 33 having the portions 34 and 35 in spaced relation and in alignment so that when the member 33 is secured to the head structure 10, these portions are in alignment with the portion 14 of the head structure. The two portions 34 and 35 are connected by an upwardly and forwardly inclined portion 36 and an inturned curved portion 37.

As shown by the dotted lines in Fig. 1, when a different size door, that is a door of different width, is employed, members of slightly different formation and dimensions are substituted for those previously set forth. The head structure includes an additional opening 127, in which is then mounted the pivot 128, supporting arm 129, in turn supporting the switch track member 131 and 130. As shown in Fig. 1, the switch track member 130 includes an extension 130a.

When the substituted switch track is mounted upon the head structure, there is substituted for the member 33, another member of similar formation but having a different forward outline, to wit, the same is provided with the upwardly and forwardly inclined portion 136 and an inwardly and upwardly curved portion 137. These substituted parts are utilized together and replace the before mentioned parts 36 and 37 which are also used together.

The head structure, as shown clearly in Fig. 1, has outlined from it a plurality of pairs of ears as at 40, 41, 42 and 43. Each of these is apertured as at 44 and the head is apertured as at 45 and 46, the latter being continuations of the severances 42 and 41, and the same being connected together so that when the ears outlined at 40, 41, 42 and 43 are turned outwardly and at 180 degrees to the portions 24, they form a four bearing support for the pulley shaft, and all the holes 44 of the four ears are in alignment. Also with this formation, there is formed an enlarged opening that is shown dotted as at 50 and through which the pulley when mounted projects. This pulley accommodates the cable or other flexible connection between the counterbalancing means and the lower door section.

Reference will now be had to Figs. 3 and 4. In this modified form of the invention, the sheet metal head structure 10 has formed integral therewith the portion 33 and it is also formed with the inclination 36 which is merged with a portion having an outline as indicated at 137, all of the aforesaid being integral. The portion 33, or more specifically that portion included and defined by the portions 35, 37 and 137, is suitably apertured and when a lower socket, such as indicated at 37, must be employed, then the additional member 250 is associated therewith and secured as at 251 so that the vertical portion 235 forms an extension downwardly of the portion 35 and the curved portion 237 merges with the portion 36 and is the equivalent of the portion indicated at 37 in Fig. 1. Preferably the aforesaid head structure is of sheet metal and of suitable thickness of stock for the purpose set forth. The two interchangeable inserts may be castings or stampings. The supplemental members shown in Figs. 3 and 4 is preferably a casting.

The invention claimed is:—

1. A head bracket for a folding sectional door including a substantially triangular plate body portion, a forwardly positioned outwardly projecting flange forming a track terminating at its upper end in a forwardly directed curved socket

forming portion, another and similarly projecting track portion substantially parallel to the other track portion and including a forwardly and upwardly directed curved portion merging with said socket and rigidly secured to the plate body and terminating at its lower end short of the first mentioned track portion termination, a guide confining hypotenuse rear edge on the body comprising a pair of reverse curves of relatively large radius, the lower end of the lower curve terminating in parallel relation to the front track portion and in alignment with the second mentioned and spaced parallel track portion providing a gap therebetween for guide passage, and a combination switch and track pivotally supported upon the plate body and arranged to initially permit the passage of a guide member therebeneath, the upper portion of the switch being engageable by the guide member and tiltable thereby for positioning the lower end of the switch adjacent the back track edge for switching purposes, the switch being automatically tilttable by the first mentioned guide member in the movement thereof.

2. A head bracket for a folding sectional door including a substantially triangular plate body portion, a forwardly positioned outwardly projecting flange forming a track terminating at its upper end in a forwardly directed curved socket forming portion, another and similarly projecting track portion substantially parallel to the other track portion and including a forwardly and upwardly directed curved portion merging with said socket and rigidly secured to the plate body and terminating at its lower end short of the first mentioned track portion termination, a guide confining hypotenuse rear edge on the body comprising a pair of reverse curves of relatively large radius, the lower end of the lower curve terminating in parallel relation to the front track portion and in alignment with the second mentioned and spaced parallel track portion providing a gap therebetween for guide passage, a combination switch and track pivotally supported upon the plate body and arranged to initially permit the passage of a guide member therebeneath, the upper portion of the switch being engageable by the guide member and tiltable thereby for positioning the lower end of the switch adjacent the back track edge for switching purposes, the switch being automatically tilttable by the first mentioned guide member in the movement thereof.

3. A head bracket for a folding sectional door including a substantially triangular plate body portion, a forwardly positioned outwardly projecting flange forming a track terminating at its upper end in a forwardly directed curved socket forming portion, another and similarly projecting track portion substantially parallel to the other track portion and including a forwardly and upwardly directed curved portion merging with said socket and rigidly secured to the plate body and terminating at its lower end short of the first mentioned track portion termination, a guide confining hypotenuse rear edge on the body comprising a pair of reverse curves of relatively large radius, the lower end of the lower curve terminating in parallel relation to the front track portion and in alignment with the

- second mentioned and spaced parallel track portion providing a gap therebetween for guide passage, a combination switch and track pivotally supported upon the plate body and arranged to initially permit the passage of a guide member therebeneath, the upper portion of the switch being engageable by the guide member and tilt-able thereby for positioning the lower end of the switch adjacent the back track edge for switch-
10 ing purposes, the switch being automatically tilt-able by the first mentioned guide member in the movement thereof, and a plurality of spaced ears extending from the plate body portion and oppositely from the forward track portion, said body portion including an aperture adjacent the ears for pulley reception, the pulley being mounted in said ears, said ears being simultaneously formed with the aperture and being integral with the plate body.
- 20 4. A head bracket for a folding sectional door including a substantially triangular plate body portion, a forwardly positioned outwardly pro-
jecting flange forming a track terminating at its upper end in a forwardly directed curved socket forming portion, another and similarly project-
ing track portion substantially parallel to the other track portion and including a forwardly and upwardly directed curved portion merging with said socket and rigidly secured to the plate body and terminating at its lower end short of the first mentioned track portion termination, a guide confining hypotenuse rear edge on the body comprising a pair of reverse curves of relatively large radius, the lower end of the lower curve terminating in parallel relation to the front track portion and in alignment with the second mentioned and spaced parallel track portion pro-
viding a gap therebetween for guide passage, a combination switch and track pivotally sup-
ported upon the plate body and arranged to initially permit the passage of a guide member therebeneath, the upper portion of the switch being engageable by the guide member and tilt-able thereby for positioning the lower end of the switch adjacent the back track edge for switch-
40 ing purposes, the switch being automatically tilt-able by the first mentioned guide member in the movement thereof, a plurality of spaced ears ex-
tending from the plate body portion and oppositely from the forward track portion, said body portion including an aperture adjacent the ears for pulley reception, the pulley being mounted in said ears, said ears being simultaneously formed with the aperture and being integral with the plate body, and an additional pair of ears integral with the body and similarly positioned at each side of the first mentioned pair of ears and axially aligned therewith for multiple bearing support purposes.
- 50 5. A head bracket for a folding sectional door including a substantially triangular plate body portion, a forwardly positioned outwardly pro-
jecting flange forming a track terminating at its upper end in a forwardly directed curved socket forming portion, another and similarly project-
ing track portion substantially parallel to the other track portion and including a forwardly and upwardly directed curved portion merging with said socket and rigidly secured to the plate body and terminating at its lower end short of the first mentioned track portion termination, a guide confining hypotenuse rear edge on the body comprising a pair of reverse curves of relatively large radius, the lower end of the lower curve termini-
70 nating in parallel relation to the front track por-
tion and in alignment with the second mentioned and spaced parallel track portion providing a gap therebetween for guide passage, and a combination switch and track pivotally supported upon the plate body and arranged to initially permit the passage of a guide member therebeneath, the upper portion of the switch being engageable by the guide member and tilt-able thereby for positioning the lower end of the switch adjacent the back track edge for switch-
80 ing purposes, the switch being automatically tilt-able by the first mentioned guide member in the movement thereof, said first mentioned forward track portion including a forward offset beneath the socket and forming a second socket therebeneath.
- 85 6. A device of the character defined by claim 5, characterized by the plate body portion and forward track portion being relieved, and the second mentioned socket forming portion constituting an adapter insert secured to and supported by said plate portion and including a portion forming the second mentioned socket.
- 90 7. A head bracket for a folding sectional door including a substantially triangular plate body portion, a forwardly positioned outwardly pro-
jecting flange forming a track terminating at its upper end in a forwardly directed curved socket forming portion, another and similarly project-
ing track portion substantially parallel to the other track portion and including a forwardly and upwardly directed curved portion merging with said socket and rigidly secured to the plate body and terminating at its lower end short of the first mentioned track portion termination, a guide confining hypotenuse rear edge on the body comprising a pair of reverse curves of relatively large radius, the lower end of the lower curve terminating in parallel relation to the front track portion and in alignment with the second mentioned and spaced parallel track portion pro-
viding a gap therebetween for guide passage, a combination switch and track pivotally sup-
ported upon the plate body and arranged to initially permit the passage of a guide member therebeneath, the upper portion of the switch being engageable by the guide member and tilt-able thereby for positioning the lower end of the switch adjacent the back track edge for switch-
100 ing purposes, the switch being automatically tilt-able by the first mentioned guide member in the movement thereof, said first mentioned forward track portion including a forward offset beneath the first socket and in alignment therewith, and an adapter insert which when mounted lowers the top portion of said second mentioned socket for the purpose set forth.
- 105 8. A head bracket for a folding sectional door including a substantially triangular plate body portion, a forwardly positioned outwardly pro-
jecting flange forming a track terminating at its upper end in a forwardly directed curved socket forming portion, another and similarly project-
ing track portion substantially parallel to the other track portion and including a forwardly and upwardly directed curved portion merging with said socket and rigidly secured to the plate body and terminating at its lower end short of the first mentioned track portion termination, a guide confining hypotenuse rear edge on the body comprising a pair of reverse curves of relatively large radius, the lower end of the lower curve termini-
110 nating in parallel relation to the front track portion and in alignment with the second mentioned and spaced parallel track portion providing a gap therebetween for guide passage, and a combination switch and track pivotally supported upon the plate body and arranged to initially permit the passage of a guide member therebeneath, the upper portion of the switch being engageable by the guide member and tilt-able thereby for positioning the lower end of the switch adjacent the back track edge for switch-
115 ing purposes, the switch being automatically tilt-able by the first mentioned guide member in the movement thereof, said first mentioned forward track portion including a second socket beneath the first socket and in alignment therewith, and an adapter insert which when mounted lowers the top portion of said second mentioned socket for the purpose set forth.
- 120 9. A head bracket for a folding sectional door including a substantially triangular plate body portion, a forwardly positioned outwardly pro-
jecting flange forming a track terminating at its upper end in a forwardly directed curved socket forming portion, another and similarly project-
ing track portion substantially parallel to the other track portion and including a forwardly and upwardly directed curved portion merging with said socket and rigidly secured to the plate body and terminating at its lower end short of the first mentioned track portion termination, a guide confining hypotenuse rear edge on the body comprising a pair of reverse curves of relatively large radius, the lower end of the lower curve termini-
125 nating in parallel relation to the front track portion and in alignment with the second mentioned and spaced parallel track portion providing a gap therebetween for guide passage, and a combination switch and track pivotally supported upon the plate body and arranged to initially permit the passage of a guide member therebeneath, the upper portion of the switch being engageable by the guide member and tilt-able thereby for positioning the lower end of the switch adjacent the back track edge for switch-
130 ing purposes, the switch being automatically tilt-able by the first mentioned guide member in the movement thereof, said first mentioned forward track portion including a second socket beneath the first socket and in alignment therewith, and an adapter insert which when mounted lowers the top portion of said second mentioned socket for the purpose set forth.
- 135 10. A head bracket for a folding sectional door including a substantially triangular plate body portion, a forwardly positioned outwardly pro-
jecting flange forming a track terminating at its upper end in a forwardly directed curved socket forming portion, another and similarly project-
ing track portion substantially parallel to the other track portion and including a forwardly and upwardly directed curved portion merging with said socket and rigidly secured to the plate body and terminating at its lower end short of the first mentioned track portion termination, a guide confining hypotenuse rear edge on the body comprising a pair of reverse curves of relatively large radius, the lower end of the lower curve termini-
140 nating in parallel relation to the front track portion and in alignment with the second mentioned and spaced parallel track portion providing a gap therebetween for guide passage, and a combination switch and track pivotally supported upon the plate body and arranged to initially permit the passage of a guide member therebeneath, the upper portion of the switch being engageable by the guide member and tilt-able thereby for positioning the lower end of the switch adjacent the back track edge for switch-
145 ing purposes, the switch being automatically tilt-able by the first mentioned guide member in the movement thereof, said first mentioned forward track portion including a second socket beneath the first socket and in alignment therewith, and an adapter insert which when mounted lowers the top portion of said second mentioned socket for the purpose set forth.
- 150

nation switch and track pivotally supported upon the plate body and arranged to initially permit the passage of a guide member therebeneath, the upper portion of the switch being engageable by the guide member and tilttable thereby for positioning the lower end of the switch adjacent the back track edge for switching purposes, the switch being automatically tilttable by the first mentioned guide member in the movement thereof, said body portion including a plurality of mountings for varying the position of the pivotal support for the support of the combination switch member, said switch track member being of predetermined conformation for the particular door size, said forward track portion including an interruption, and a socket forming adapter operatively associated with the interruption for closing the same and forming a second socket in the forward track portion, said adapter having a conformation specific to the selected size of door, said conformation of the adapter and a switch cooperating each with the other for door operation.

9. A head bracket for a folding sectional door including a substantially triangular plate body portion, a forwardly positioned outwardly projecting flange forming a track terminating at its upper end in a forwardly directed curved socket forming portion, another and similarly projecting track portion substantially parallel to the other track portion and including a forwardly and upwardly directed curved portion merging with said socket and rigidly secured to the plate body and terminating at its lower end short of the first mentioned track portion termination, a guide confining hypotenuse rear edge on the body comprising a pair of reverse curves of relatively large radius, the lower end of the lower curve terminating in parallel relation to the front track portion and in alignment with the second men-

tioned and spaced parallel track portion providing a gap therebetween for guide passage, a combination switch and track pivotally supported upon the plate body and arranged to initially permit the passage of a guide member therebeneath, the upper portion of the switch being engageable by the guide member and tilttable thereby for positioning the lower end of the switch adjacent the back track edge for switching purposes, the switch being automatically tilttable by the first mentioned guide member in the movement thereof, said body portion including a plurality of mountings for varying the position of the pivotal support for the support of the combination switch member, said switch track member being of predetermined conformation for the particular door size, said forward track portion including an interruption, a socket forming adapter operatively associated with the interruption for closing the same and forming a second socket in the forward track portion, said adapter having a conformation specific to the selected size of door, said conformation of the adapter and a switch cooperating each with the other for door operation, a plurality of spaced ears extending from the plate body portion and oppositely from the forward track portion, said body portion including an aperture adjacent the ears for pulley reception, the pulley being mounted in said ears, said ears being simultaneously formed with the aperture and being integral with the plate body, and an additional pair of ears integral with the body and similarly positioned at each side of the first mentioned pair of ears and axially aligned therewith for multiple bearing support purposes.
